UNITED STATES PATENT OFFICE.

WALTHER AKEMANN, OF ESSEN, GERMANY, ASSIGNOR TO FRIED. KRUPP AKTIEN-
GESELLSCHAFT, OF ESSEN-ON-THE-RUHR, GERMANY.

FIRE-DIRECTION APPARATUS FOR NAVAL GUNS.

Application filed November 10, 1920. Serial No. 423,118.

To all whom it may concern:

Be it known that I, WALTHER AKEMANN, residing at Essen, Germany; a citizen of the German Republic, have invented a certain new and useful Improvement in Fire-Direction Apparatus for Naval Guns, of which the following is a specification.

The present invention relates to fire control apparatus for naval guns which are provided with electric devices for firing at a distance, so that the guns may be fired not only with the ship at rest, but also when the ship pitches hard. For this purpose fire control apparatus of known design is provided with a device which makes it possible to close the firing circuit at an instant, which lies an amount of time ahead of the moment when the pitching ship passes through its horizontal position, said time amount corresponding to the given firing retardation.

The subject matter of the invention resides in a fire control apparatus of known art with improvements for measuring and indicating the angular speed of the pitching of the ship, so that the pre-ignition angle may be constantly adapted to the changes of the angular speed of the pitching; said pre-ignition angle corresponding to the above named amount of time. The device for distance firing may also be accurately inserted at the instant which lies ahead of the moment when the projectile has to leave the gun, an amount of time equal to the required pre-ignition angle corresponding to the angular velocity of pitching. A further advantage of the invention resides in the fact that this instant is independent of whether the ship pitches upwards or downwards, so that firing may take place in both directions of pitching when the ship passes through its horizontal position, whereby a considerable increase in the firing speed is attained.

One embodiment of the invention is illustrated on the drawing in—

Fig. 1, which shows a diagrammatic representation of the fire control apparatus, and

Fig. 2, a modification of one of the details.

The embodiment represented in Fig. 1, will first be described, where the fire control apparatus consists mainly of three widely separated devices denoted by Roman figures I, III, and IV in the figure and connected

by electric conductors. The Roman figure II, denotes a side-view and part section along line 2—2 of the upper portion of part I in Fig. 1. The device I and II in Fig. 1, for measuring and distance transmission of the angular speed of the pitching, comprises a fixed stand A, a member a^2 revolvable around the perpendicular axis of the stand when the ship is at rest, by means of a pivot a' ; and also a gyroscope housing a^3 containing a firing gyroscope which is oscillatable upon the member a^2 around a horizontal axis with the ship at rest. The housing a^3 has in general a spherical shape. It is provided with a tooth rack a^4 on its under side, in mesh with a worm a^5 mounted in the revolvable member a^2 . The worm a^5 receives its motion from a motor A⁶ which is also placed on the revolvable member a^2 . To rotate the member a^2 around the axis of the pivot a' is provided a driving shaft B with a hand wheel b' , positively connected with the member a^2 by means of a pair of bevel wheels b^2 a^9 and a worm gear a^7 a^8 , said shaft B being mounted on a stationary part in the manner indicated on the drawing. For reading the training given the member a^2 is provided a drum b^3 keyed fast upon the driving shaft B and the cooperating index finger b^4 . In the gyroscope housing a^3 are revolvably mounted two coaxial shafts a^{11} secured on the gyroscope frame a^{10} . The shafts a^{11} penetrate on both sides through the gyroscope housing a^3 and carry two telescopes a^{12} and a^{13} with parallel sight lines, upon the ends extending through the housing. The telescope a^{12} is intended to keep the horizon in sight, while the other a^{13} serves as the principal range telescope. The gyroscope a^{14} mounted in the frame a^{10} and revolvable around a vertical axis while the ship is at rest is of well known construction. An electric motor (not shown) is provided particularly for driving the gyroscope a^{14} .

The gyroscope housing a^3 is provided with an enlargement a^{15} on the side nearest the telescope a^{13} . In this enlargement a^{15} are enclosed a small dynamo comprising a magnet field a^{16} and an armature a^{17} , and a transmitter of a device for distance transmission of the angular position, said transmitter also comprising a magnet field a^{18} and an armature a^{19} . Both the armature a^{17} and the armature a^{19} are keyed

to the telescope shaft a^{11} . By means of a relative movement of the enlargement a^{15} , fixedly connected with gyroscope housing a^3 , in relation to the axis of the shaft a^{11} , a rotation of the same magnitude then takes place both between the dynamo-armature a^{17} and the magnet field a^{16} , as also between the transmitter armature a^{19} and its magnet field a^{18} . On the shaft a^{11} are further provided two slip rings a^{20} which are connected with the ends of the winding of the dynamo-armature a^{17} . Against the slip rings a^{20} press brushes a^{21} , which are intended to collect the induction current from the armature a^{17} . With constant strength of a magnet field a^{16} , the tension between the two slip rings a^{20} becomes directly proportionate to the angular velocity of the armature a^{17} as regards the magnet field a^{16} and consequently also with the angular velocity with which the gyroscope housing a^3 turns as regards the gyroscope frame a^{10} . As, however, the first named angular velocity coincides with the ship's pitching angular velocity, then the tension present at the brushes constitute a direct measure of the angular velocity of the pitching of the ship. On the inner wall of the gyroscope housing a^3 is provided a contact tongue a^{22} , situated in a firing circuit, described hereinafter, and with which another contact tongue a^{23} may cooperate, said last named tongue a^{23} being attached to the gyroscope frame a^{10} and also situated in the above named firing circuit. By turning the gyroscope housing a^3 relatively to the gyroscope frame a^{10} , the angle may be set, which the two contact tongues form with each other and as a consequence also the moment in which the firing circuit is closed, determined. With the driving shaft B intended for the setting of the side-direction is connected still another device for distance transmission of the side-direction or transversing angle, said device being constructed for coarse and fine adjustment in well known manner. This device consists mainly of two revolvable armatures C and D within corresponding magnet fields C' and D' , said armatures being positively connected with the driving shaft B through the intermediary of a pair of bevel gears b^6 d^2 , b^8 e^2 in such manner that the entire adjustment extent of the drum b^8 corresponds to a single revolution of the armature D and several revolutions of the armature C . The magnet fields C' and D' are revolvable around the axes of the armatures C and D . The magnet fields are adjusted by a shaft E provided with a hand wheel e' and positively connected to the magnet fields C' and D' by a worm wheel gearing e^2 , d^2 and a spur wheel gearing e^8 , c^2 . The gear ratios of the gears e^2 d^2 and e^8 c^2 have been so selected that the ratio of the

revolving speed of the magnet field D' in relation to that of the magnet field C' is the same as the ratio of the revolving speed of the armatures D and C . A scale drum e^4 keyed upon the shaft E , together with the pointer e^5 serve to read the angular position given the magnet fields. The last described contrivance serves to vary the side-direction or traversing angles to which the coarse transmitter D D' and the fine transmitter C C' have been adjusted, without turning the member a^3 and with it the gyroscope housing a^3 around its vertical axis, that means without having to move the sight telescope a^5 out of its direction on the target.

The device, shown at III Fig. 1, erected on the commanding officer's stand contains first a transmitter for distance transmission of the elevating angle to the gun to be pointed. The transmitting-armature of this transmitter is formed by a cylinder F' covered with lamellae and freely revolvable around a shaft F . These lamellae are electrically connected with the individual steps of a resistance coil F^2 excited by a direct current source. Upon the lamellar surfaces of the transmitter armature F' rest three brushes f^3 disposed 120° from each other and connected by means of conductors f^4 with a receiver-motor G erected at the gun, Fig. 1. The armature of this motor is positively connected with the toothed arc of the elevating gear in the manner shown at IV. This contrivance makes it possible to give the gun H the elevation corresponding to the range by turning the transmitter armature F' . A driving shaft J provided with a hand wheel z' serves to turn the armature F' by means of a bevel gear train i^2 f^5 f^6 in the manner shown at III. The elevating setting given to the armature F' and, through it, to the gun H may be read off on a range drum i^2 and a pointer N belonging thereto, said drum being keyed to the shaft J .

The transmitter contrivance comprises moreover a transmitter for distance adjustment to the pre-igniting angle of the housing a^3 and, through it, of the control tongue a^{22} of the firing wheel, said angle corresponding to the angular speed of the pitching. This transmitter consists, similarly to the one already described, of an armature K fed by direct current through resistance coils, and from which a multiple phase current may be collected by means of three slide brushes K' set 120° apart. From the slide brushes K' connection conductors k^2 lead to the receiver motor A^6 , which serves to drive the gyroscope housing a^3 around its axis that is horizontal during the ship's position of rest. The transmitter armature K is driven by a hand wheel M through several intermediary gears the object and arrangement of which will be described hereinafter.

The scale disc N has also positive driving

connection with the shaft m' of this hand wheel by means of a worm gear $m^2 n^4$. The scale disc N carries a mark n^2 , called follower or trailer mark, which is intended to be held continuously in agreement with an index N' revolvable in relation to the scale disc N . This index N' constitutes a portion of the indicating device for the ship's pitching angular velocity. For this purpose it is secured on a rotatable coil n^3 which has electrical connection through conductors a^{24} with the slide brushes a^{21} inserted in the extension a^{15} of the gyroscope housing a^3 . The deflection of the index N' in either direction does consequently constitute a measure for the speed of the relative movement between the armature a^{17} and the magnet field a^{16} of the dynamo situated in the gyroscope housing and as a consequence also a measure for the ship's pitching angular velocity.

The index N' and its mark n^2 form simultaneously two contacts of the already mentioned firing circuit which also contains a conductor n^5 , a battery N^6 , a two poled switch N^7 , a conductor n^8 with the coil n^9 of a firing magnet, as well as the contact tongues a^{22} and a^{23} connected with conductors a^{25} . It is now so arranged that the firing circuit containing the contact tongues a^{22} and a^{23} will be closed upon switching in of the switch N^7 as soon as the contact tongues a^{22} and a^{23} touch, when the angular positions of the index N' and the mark n^2 coincide.

The driving shaft m' for the disc N provided with the hand wheel M carries on its free end a friction disc m^3 cooperating with a second disc p' , which is secured on the end of a revolvable and displaceable shaft P . Upon this shaft P is keyed a spur gear p^2 of such a width that it cooperates with a spur gear p^4 keyed on an intermediary shaft p^3 , in all positions of the shaft P . The intermediary shaft p^3 carries in addition a bevel gear p^5 , which is in mesh with a bevel gear k^4 on a shaft k^3 . This shaft k^3 carries on its end, bent out at right angles a loose running bevel gear k^5 which turns with the shaft k^3 and, as a consequence, cooperates with a bevel gear k^6 keyed upon the shaft of armature K . For displacing the shaft P , together with the friction disc p' relatively to the friction disc m^3 , a tooth rack p^6 is provided which is connected through a coupling with the shaft P and is in mesh with a pinion p^7 having an operating crank p^8 . The displacement of the shaft P makes it possible to change the ratio of the gearing intended for driving the transmitter K and the displacement of the contact tongues a^{22} and a^{23} . This device is used when it is necessary to change the pre-ignition which corresponds to the angular velocity of pitching to agree with alteration of muzzle velocity

of the projectile or the inertia of the firing magnet.

At the commanding officer's stand is to be found still another contrivance which permits of firing under continuous inclination of the ship, that is when the ship does not pass through its horizontal position, this firing then taking place when passing through a middle inclined position which differs from the horizontal position by a certain amount, the so called heeling angle. For this purpose is first provided a pitching angle indicator, which is conveniently positioned so as to be seen by the gunner who attends to the hand wheel i' for elevating the gun. The pitching angle indicator consists of a receiver armature q' with which an index Q , revolvable upon a fixed scale disc Q^2 shows whether the ship passes through the horizontal position during the pitching or not. By means of conductors q^4 , the receiver armature q' is connected with the magnet field a^{18} of the transmitter arranged on the firing gyroscope a^{14} in such a manner that the index Q reproduces accurately the angular pitching movement of the magnet field a^{18} .

Near the pitching angle indicator Q , Q^2 is placed a shaft R having a hand wheel r' upon which is mounted a spur gear r^2 . The latter is in mesh with a spur gear f^7 on the one hand and with a spur gear k^7 on the other hand. The spur gear f^7 is mounted upon the shaft F , one end of which being provided with an arm at right angles which arm carries the spur gear f^5 . The spur gear k^7 is by means of a hollow shaft k^8 connected with the bevel wheel k^9 , with which bevel pinion k^5 is in mesh. This pinion k^5 meshes on the other hand with the bevel gear k^6 , upon the shaft of which the transmitter armature K is keyed; said bevel pinion k^5 being mounted on an arm but at right angles from the shaft k^8 , which latter runs through the hollow shaft k^8 and carries the above named bevel gear k^4 at its other end. It is consequently so arranged that a rotation of the hand wheel r' influences the revolving speed of the transmitter armatures F' and K and in the same direction through the bevel gears $f^5 f^6$ and $k^5 k^6$. It is therefore possible to transmit both to the armature F' and to the armature K an additional rotation corresponding to the deflection of the index Q independent of whether the hand wheels M and i' have already been moved or not.

A receiver contrivance for coarse and fine setting of the side direction is provided on the gun, see at IV, Fig. 1, beside the elevating motor G and the firing magnet n^9 . This receiver contrivance may be constructed in accordance with my Patent No. 1,166,034 dated December 15th, 1915. The coarse-re-

ceiver S , constructed as a drum, is connected through conductors s' with the transmitter field D' provided at the gyroscope station; and the similarly constructed fine-receiver S^2 connected through conductors s^2 with the transmitter field C' , in such a manner that both reproduce the relative movement between the armatures C and D and their corresponding magnet fields C' and D' accurately as to the angles. For reading the setting there is provided for each an angular graduation upon the dial surface (not shown) and a fixed reading mark. In the immediate neighborhood of the receiver-indicator contrivance are to be found two dials S^4 and S^5 exactly like the dials S' and S^2 , also provided with similar angular graduation (not shown) and which dials have positive driving connection with the toothed wheel T . The gun is trained in azimuth by hand by means (not shown), the readings of the dials S^4 S^5 being kept in coincidence with those of the dials S S^2 , intended for laying the gun in azimuth.

In describing the manner of operation it will be supposed that the parts from the start have the relative position shown. It will furthermore be supposed that the ship is in a horizontal floating position. By first turning the handwheel b' the revolvable member a^2 with gyroscope housing a^3 is rotated on its pivot a' until the telescope a^{13} is directed towards the target. Through the intermediary of the gear train and electrical transmitters B b^5 c^2 b^6 d^2 C D C' D' s^2 s' which serves for distance adjustment of the side direction (traversing), the drums S and S^2 (at IV) partake in the rotation of the handwheel b' in such a manner that they turn the same angle as the gyroscope housing a^3 whereby the side direction against the target may be communicated to the gun. A correction of the side direction, in order for instance to take care of the drift of the projectile or the horizontal difference between the position of the gun and the gyroscope may be accomplished by turning the hand wheel c' , which causes a displacement of the transmitter fields C' and D' , without that the gun loses its direction towards the target. Simultaneously the hand wheel i' (at III) is turned until the gun II, connected therewith by means of the gear train and electrical transmitters J i^2 f^5 f^6 F' f^3 f^4 G , has received the required elevation corresponding to the range. As soon as the gun in this manner has been directed upon the target by elevation and training, it may at any time be fired through the closing of the switch N^7 if the ship lies still.

Should however, the gun, in the above named manner directed against the target by elevating and training, have to be fired at the moment of passing through its horizontal position when the ship pitches, then

the firing circuit must be closed at a moment which lies a certain interval ahead of the moment at which the ship reaches its horizontal floating position, independent of whether the pitching of the ship takes place upwards or downwards. This interval is directly proportionate to the angular pitching velocity and the firing retardation (that is, the time which elapses from the moment of closing the firing circuit until the moment when the projectile leaves the muzzle of the gun). As the firing retardation to a great extent is independent of the strength of the propelling charge and the inertia of the firing magnet, it may generally be considered as a constant quantity, and as a result, the above named interval is directly proportionate to the continuously changing angular pitching velocity.

In accordance with the above, the friction disc p' , while the ship is pitching, is first adjusted by turning the crank p^8 , so that the gear ratio of the changed gearing, formed by the discs m^3 p' , exactly expresses the firing retardation. Thereupon the graduation disc N is constantly adjusted by turning the hand wheel M , so that the mark n^2 agrees continuously with the index N' . Through the intermediary of the gear train and electrical transmitters m^3 p' P p^2 p^4 p^5 p^6 k^4 k^5 k^6 K k^1 k^2 A^6 , the housing a^3 with the contact tongue a^{22} rigidly connected thereto partake in the turning of the driving shaft m' in such a manner that they move downwards during upward pitching and vice versa.

As the rotating angle of the shaft m' during the above mentioned turning is always proportionate to the pitching angle velocity and the change gear m^3 p' correctly expresses the firing retardation, it then follows that the rotating angle of the transmitter K and with it also the contact tongue a^{22} is always proportionate to the product of the firing retardation and the pitching angle velocity.

The additional rotation given the index N' through the last mentioned displacement of the housing a^3 , is generally so small that it is permissible to neglect it. It may, however, also be completely eliminated by arranging for instance the magnet field a^{16} upon a part which does not partake in the setting movement of the contact tongue a^{22} upon such a part, for instance, as a stand rigidly fastened to the ship's deck.

When the mark n^2 coincides with the index N' , electric contact will simultaneously be established between these parts, so that the firing circuit fed from the battery N^6 will be closed at this place. If now the switch N^7 is closed while the pitching movement is reversed, then the firing circuit will be closed, during continued pitching, through the contacting of the contact

tongues a^{22} and a^{23} at the instant which exactly expresses the pre-igniting angle given the contact tongue a^{22} by the driving member M. The projectile therefore leaves the muzzle of the gun at the exact moment when the ship reaches its horizontal floating position.

In case the ship should not happen to pass the horizontal floating position during its pitching as often happens, but that instead the pitching takes place around a position of rest which differs from the horizontal position by a heeling angle $\pm \alpha$, then this inclined position of the ship must be taken into account both as regards the distance transmitting contrivance as also with regard to the firing gyroscope. For this purpose the hand wheel r' at the commanding officer's stand, has to be turned until the gun has attained an elevation through the intermediary of the gear train $R r^2 f^1, F f^3 f^6 F' f^3 f^4 G$, that equals the elevating angle corresponding to the range, plus (or minus) the heeling angle α of the ship; and until also the housing a^9 has obtained such a rotation, by means of the gear train and electrical transmitters $R r^2 k^7 k^8 k^9 k^5 k^6 K k' k^2 A^6$, that the index Q of the pitching angle indicator also is rotated an angle $\pm \alpha$ as regards a horizontal plane. If now the pre-igniting angle, which corresponds to the existing pitching angular velocity, is adjusted upon the firing gyroscope, by correct following between the index N' and the mark n^2 by means of the hand wheel M, then the projectile must leave the gun-muzzle at the instant the ship passes its position of rest, in other words, at that instant when the gun is inclined at an elevating angle which corresponds to the range $\pm$ the heeling angle α as regards the ship's deck, that is the elevating angle as regards the horizontal plane.

The independence of the pre-igniting angle both of the magnitude of the firing retardation and of the variable pitching angle velocity may also be attained in a different manner than by means of a change gear formed by adjustable friction discs.

If, namely, (see Fig. 2) in the circuit a^{24} leading from the slip brushes a^{21} on the gyroscope casing, there being inserted in series a fixed resistance a^{29} and a variable resistance a^{26} , instead of directly inserting the rotating coil of the velocity index, the magnitude of said resistance being changeable according to the position of a control lever a^{27} corresponding to the adjustment of the firing retardation; and if, furthermore, the rotating coil a^{28} being connected in closed parallel circuit, being shunted across variable resistance a^{28} , from one end of said resistance to the fulcrum of contact lever a^{27} , then the index (not shown) does no longer give the value of the pitching angle

velocity, but instead directly that of the product of the pitching angle velocity and of the firing retardation.

This product must, however, as has already been explained, be proportionate to the pre-ignition angle to be set on the firing gyroscope. It is therefore sufficient to turn the hand wheel M, compare Fig. 1 at III, so that the mark n^2 remains constantly in coincidence with the index N' . By means of the shaft m' , which is supposed to be directly connected with the shaft k^3 through its extension, that rotation will then always be transmitted to the transmitter armature K which is necessary for the correct distance adjustment of the pre-ignition angle proportionate to the above named product.

Instead of firing only one gun, several guns may naturally be fired simultaneously from one commanding station, and for this only a single firing gyroscope is needed, while one or more transmitters may be utilized for the elevation.

Claims:

1. A fire control apparatus for naval guns comprising a stabilizing device, means for measuring and indicating the pitching angular velocity of the ship and means for manually adjusting the pre-ignition angle corresponding to the indications of the measuring and indicating means, said first named means being connected to and operable by the stabilizing device.

2. A fire control apparatus of the class described for naval guns comprising a stabilizing device supporting a sighting telescope, a casing for said stabilizing device, a firing circuit, a pair of firing tongues interposed in said circuit, one of said firing tongues being supported by said casing and the other by said stabilizing device, means for measuring the pitching angular velocity of the ship, said means being connected to and operable by the stabilizing device and means cooperable with said pitching angular velocity measuring means operably connected to the first mentioned firing tongue for setting the proper ignition angle.

3. A fire control apparatus for naval guns comprising a stabilizing device, a casing therefor, a firing circuit, a pair of firing tongues interposed in said circuit, one of said firing tongues being supported by said casing and the other by said stabilizing device, means for indicating the pitching angular velocity of the ship, said means being connected to and operable by the stabilizing device and means cooperating with said pitching angular velocity indicating means for adjusting the first mentioned tongue to correspond to its readings.

4. A fire control apparatus of the class described comprising a stabilizing device, a casing therefor, a firing circuit, a pair of firing tongues interposed in said circuit, one

of said firing tongues taking part in the pitching movement of the ship, means for indicating the pitching angular velocity of the ship, said means being operatively connected to the stabilizing device, a trailer mark cooperating therewith, means for adjusting said trailer to correspond to the position of the pitching angular velocity indicator, said means being operatively connected by an electrical long distance transmission to the firing tongue which takes part in the pitching movement of the ship.

5. A fire control apparatus for naval guns comprising a stabilizing device, a firing circuit, a pair of firing tongues interposed in said circuit, one of said firing tongues being stabilized by said stabilizing device, the other of said firing tongues taking part in the rolling movement of the ship, means for 10 indicating the pitching angular velocity of the ship, said means being connected to and operable by the stabilizing device, said means being provided with a pointer, a cooperating trailer adjustable to correspond to 15 the reading of said pointer, means for adjusting said trailer, said means being connected to the second mentioned firing tongue by an electrical long distance transmission, said pointer and trailer being included in 20 said firing circuit.

6. A fire control apparatus of the class described comprising a stabilizing device, a shaft therefor, a casing for said stabilizing device which takes part in the rolling movement of the ship, means for indicating the pitching angular velocity of the ship, said means being controlled by the stabilizing device, means for indicating the pitching angle, a magnet system carried by 35 said casing, an armature supported upon the shaft of the stabilizing device, a receiver forming a part of the pitching angle indicating means, said magnet system, armature and receiver forming a part of an electrical long distance transmission for operating 40 said pitching angle indicator.

7. A fire control apparatus of the class described comprising a stabilizing device, a casing therefor, a pair of firing tongues, a circuit including said firing tongues, one of said firing tongues being supported by 45 said casing, the other of said firing tongues being controlled by said stabilizing device, means for indicating the pitching angular velocity of the ship, said means being controlled by the stabilizing device, a trailer 50 cooperating with the first mentioned indi-

cating means, an operating member for adjusting said trailer, a transmitter operatively connected to said operating member, 60 said transmitter forming part of an electrical long distance transmission for adjusting the firing tongue mounted upon the stabilizing device casing, a pitching angle indicator, and means for additionally adjusting the transmitter to correspond to the reading of the pitching angle indicator.

8. A fire control apparatus of the class described comprising a stabilizing device, a casing therefor, a pair of firing tongues, a 70 firing circuit including said tongues, one of said tongues being supported by said casing, means for indicating the pitching angular velocity of the ship, said means being provided with a pointer, a cooperating 75 trailer mark adjustable for coincidence with said pointer, an operating member for said trailer, a transmitter, means including a change speed gearing for connecting said operating member to said transmitter, a receiver motor operatively connected to the stabilizing device casing, means electrically connecting said transmitter and receiver motor, whereby said casing may be moved 80 to adjust the firing tongue carried thereby.

9. A fire control apparatus of the class described comprising a stabilizing device, a casing therefor, a pair of firing tongues, a firing circuit including said tongues, one of said tongues being supported by said casing, means for indicating the pitching angular velocity of the ship, said means being provided with a pointer, a cooperating pointer, an operating member for said pointer, a transmitter, means including a change speed 90 gearing for connecting said operating member to said transmitter, said change speed gearing comprising a pair of friction discs, one of said friction discs being adjustable radially of the other, a receiver motor operatively connected to the casing of the stabilizing device, said receiver motor and transmitter being operatively connected and forming an electrical long distance transmission, whereby upon adjustment of the 100 pointer the casing of the stabilizing device may be moved to adjust the firing tongue to the pre-ignition-angle.

The foregoing specification signed at Essen, Germany, this 16th day of June 1920.
